REFRIGERATING APPARATUS

Philip M. Bratten, Fort Worth, Tex., assignor to
General Motors Corporation, Dayton, Ohio, a
corporation of Delaware

Application March 17, 1936, Serial No. 69,352

2 Claims. (Cl. 211—153)

The present invention relates to refrigerator cabinets and particularly to an arrangement of means for indicating temperatures existing within such cabinets.

5 I am aware of the fact that refrigerator cabinets have, in the past, been equipped with means to indicate the temperature of a compartment within the cabinet but such means has heretofore either been constructed in an insulated wall of 10 the cabinet, with provisions for viewing the means from the exterior thereof, or positioned within the food storage compartment of the cabinet in such a position that it occupies a portion thereof adapted to receive articles to be stored therein, or the 15 indicating means has been mounted on a cooling element or evaporator of a refrigerating system positioned in the compartment. It is very difficult to seal or insulate the means which permits a thermometer, constructed in an insulating wall of a cabinet, to be viewed from the exterior 20 of the cabinet and the cost of such a structure is prohibitive. When a thermometer is placed in a food compartment of a refrigerator cabinet in a position adapted to be occupied by articles to be stored in the compartment it is likely to be broken 25 during transference of food to and from the compartment. A thermometer mounted on a cooling element positioned in a food storage compartment of a refrigerator cabinet will not indicate the true temperature of air circulating within the 30 compartment due to its being affected by the low temperature of the cooling element. Thus it is apparent that these former provisions of a temperature indicating means for food compartments 35 of refrigerator cabinets have either been too expensive to produce or have not been entirely satisfactory. My invention is directed to overcoming difficulties encountered in the production and use of these prior temperature indicating 40 means.

An object of the present invention is to provide a refrigerator cabinet with a thermometer for indicating the temperature therein and to mount the thermometer in the food storage compartment 45 thereof in a conspicuous but out of the way position so that the same will not interfere with the transference of objects to and from the food compartment.

Another object of the invention is to mount a 50 thermometer within the food storage compartment of a refrigerator cabinet in a position whereby the thermometer will not occupy a portion of the compartment adapted to receive and support articles to be stored therein.

55 A further object of the invention is to provide

a means for supporting a thermometer within the food storage compartment of a refrigerator cabinet which means forms a protecting shield for the thermometer and serves another purpose as well.

In carrying out the foregoing objects it is a still further and more specific object of the present invention to provide a depression or well in a shelf, adapted to be positioned in a food storage compartment of a refrigerator cabinet, for the reception and support of a thermometer below the food supporting surface of the shelf.

Further objects and advantages of the present invention will be apparent from the following description, reference being had to the accompanying drawing, wherein a preferred form of the present invention is clearly shown.

In the drawing:

Fig. 1 is a front perspective view of a refrigerator cabinet having a food supporting shelf 20 therein constructed in accordance with the present invention;

Fig. 2 is an enlarged fragmentary top plan view of a shelf shown in Fig. 1 and having the invention embodied therein;

Fig. 3 is a front view of the shelf shown in Fig. 2;

Fig. 4 is a sectional view through the shelf taken on the line 4—4 of Fig. 2; and

Fig. 5 is a perspective fragmentary view looking down on the upper surface of the shelf.

Referring to the drawing, for the purpose of illustrating my invention, I have shown in Fig. 1 thereof a refrigerator cabinet of the household type generally represented by the reference character 10. Cabinet 10 includes a plurality of insulating walls 11 preferably covered by a metal shell or a plurality of metallic panels. The walls 11 surround or enclose a metallic liner member 12 which forms walls of a food storage chamber 14 within cabinet 10. Any desirable or conventional cooling element or evaporator 15 of a mechanical refrigerating system is preferably mounted within the food storage chamber 14 by being suspendingly supported from the top wall 45 thereof. The refrigerating effect produced by evaporator 15 cools and causes circulation of air within chamber 14. One of the walls 11 is provided with an opening affording access to chamber 14 and which opening is normally closed by 50 a door 16. In order to divide chamber 14 into a plurality of superimposed food storage compartments or food supporting surfaces I provide a plurality of horizontally disposed reticulated shelves 18 within chamber 14. The shelves may 55

be supported in any suitable or desirable manner within chamber 14 such, for example, as by the shelf supports 19 secured to the vertical side wall portions of the metallic chamber liner 12.

5 The shelves shown in Fig. 1 of the drawing are all similarly constructed but it will be noted by referring to Fig. 2 of the drawing that one of the shelves 18 comprises a relatively heavy round wire rim member 21 which forms the peripheral edges of the shelf and is adapted to have portions thereof engaged by the supports 19. A plurality of small round wires 22 are spaced apart a predetermined distance and extend parallel to one another from the front to the rear of the rim member 21. It will be noted, by reference to Figs. 3 and 4 of the drawing, that the wires 22 are all disposed on the same horizontal plane and provide the shelf 18 with a flat food supporting surface. The ends of wires 22 are preferably 10 welded or otherwise secured within suitable slots 23 cut in or provided along the inner top surface of rim member 21. The reticulated shelf 18 has a portion thereof adjacent its front edge and inwardly of the rim member 21 indented to provide an elongated pocket or well of predetermined 15 length for the reception of an article such as a means for indicating the temperature existing within the food storage chamber 14. This pocket or well in the present disclosure is formed by a substantially semi-cylindrical and vertically disposed bent down portion 24 provided on each of certain adjacent parallel wires 22. It will be noted that the elongated pocket or well is disposed along or adjacent to one edge of shelf 18 20 and that this edge preferably forms the front of shelf 18 when same is placed in the chamber 14. The pocket or well, formed by the indented or bent down portions 24 of certain adjacent wires 22, is preferably of such depth as to permit an article such as a thermometer to be supported 25 therein below the plane of the flat food supporting surface of the shelf provided by the plurality of cross wires 22. In the present disclosure a thermometer, generally represented by the reference character 26, is shown as being supported 30 within the well or pocket. The thermometer 26 may be of any suitable or conventional construction and it will be noted by referring again to Fig. 1 of the drawing that the thermometer 26 is adjacent the access opening, adapted to be 35 closed by door 16, so as to be in a readily accessible or visible position for reading the temperature indicated thereby. The thermometer 26 may be positioned so as to be visible and readable 40 on a horizontal plane with shelf 18 but it is preferably positioned within the well or pocket so as to be visible or readable by viewing same from a point above the shelf 18 as shown in the drawing.

45 The construction of the thermometer, generally indicated by the numeral 26, in the present disclosure includes a glass tube 27 having metal cap members 28 secured to the ends of tube 27 and sealed to these ends. The tube 27 and closure caps 28 form a chamber or housing having a flat plate 29 positioned therein which plate is graduated in any suitable manner. A small glass tube 31 having mercury or other suitable fluid sealed therein is attached in any desirable manner to the plate 29. The mercury within the tube 31 is adapted to cooperate with and move 50 relative to the graduations on plate 29 in response

to temperature changes for indicating the temperature existing within the food storage chamber 14. The housing or chamber, formed by the glass tube 27 and cap members 28, prevents the thermometer element disposed therein from being directly exposed to air within the room in which the refrigerator cabinet is located when the door 16 of cabinet 10 is opened. Thus the thermometer 26 will indicate the true temperature within chamber 14 for a considerable length 10 of time after the door 16 has been opened.

5 From the foregoing it is apparent that I have provided an improved mounting of a temperature indicating means within a refrigerator cabinet. By providing for the support of a thermometer by and below the food supporting surface of a shelf disposed within a food storage chamber of a refrigerator cabinet the thermometer does not interfere with the storage of articles adapted to be placed on and supported by the food supporting surface of the shelf. The improved shelf having the well or pocket indented or formed therein locates the thermometer in the present disclosure immediately adjacent the bottom thereof out of the way of articles or food products 20 adapted to be placed on a lower shelf. The deformation of certain parts of the shelf to form the thermometer well or pocket provides a protecting shield for a thermometer adapted to be disposed in the well or pocket to thus prevent 25 breakage of the thermometer.

While the form of embodiment of the present invention as herein disclosed, constitutes a preferred form, it is to be understood that other forms might be adopted, all coming within the 35 scope of the claims which follow.

What is claimed is as follows:

1. A shelf adapted to be supported in a food storage compartment of a refrigerator cabinet comprising, a rim member, a plurality of spaced apart members disposed in the same plane and extending from one side to the opposite side of said rim member to form a substantially flat food supporting surface for said shelf, certain of said spaced apart members being bent downwardly of 40 certain other of said members adjacent said rim member and forming a pocket for the reception of a temperature indicating means below said food supporting surface, and the certain other of said members adjacent said pocket forming stop 45 means for preventing movement of the temperature indicating means adapted to be positioned in said pocket.

2. A shelf adapted to be supported in a food storage compartment of a refrigerator cabinet comprising, a rim member, a plurality of spaced apart members disposed in the same plane and extending from one side to the opposite side of said rim member to form a substantially flat food supporting surface for said shelf, certain of said 50 spaced apart members being bent downwardly of certain other of said members adjacent said rim member and forming an elongated pocket extending parallel to said rim member for the reception of a temperature indicating means below said 55 food supporting surface, and the certain other of said members adjacent said elongated pocket forming stop means for preventing longitudinal movement of the temperature indicating means adapted to be positioned in said elongated pocket 60

70 relative thereto.

PHILIP M. BRATTEN.
